UNITED STATES PATENT OFFICE.

JULIUS MALLETT, OF ST. LOUIS, MISSOURI.

SAFETY FOOT-GUARD FOR RAILWAY-CROSSINGS.

1,329,789.

Specification of Letters Patent.

Patented Feb. 3, 1920.

Application filed October 27, 1919. Serial No. 333,641.

To all whom it may concern:

Be it known that I, JULIUS MALLETT, a citizen of the United States, residing at St. Louis, in the State of Missouri, have invented certain new and useful Improvements in Safety Foot-Guards for Railway-Crossings, of which the following is a specification containing a full, clear, and exact description, reference being had to the accompanying drawings, forming a part hereof.

My invention relates to an improved safety foot-guard for railway crossings, and it consists in the novel construction and combination of parts that I have herein-15 after particularly described and distinctly claimed.

The object of my invention is to provide a safety foot-guard for railway crossings that will prevent the heels of a person's shoes using the crossing from being accidentally caught in the space that now exists between the rails of the railway-track and the boards or planks that are used as a foot-crossing for persons and animals, and which 20 guard will also close up the said dangerous space at all times (except when a locomotive or train is passing along the rails at said crossing) and thereby prevent the accidental entrance into said space of any part of a person's shoe, foot, hand or clothing accidentally, as well as the entrance accidentally into said space of the feet or shoes of horses and other animals; whereby the loss of life and limbs at such crossings will be done 25 away with by reason of the abolishment of said dangerous space between the said rails and the boards or planks of the foot or vehicle crossing, of a steam or electric railway.

40 In the drawings,

Figure 1 is a top plan-view of a portion of a railway crossing, having my invention applied thereto, and

Fig. 2 is a fragmentary vertical trans-45 verse section of the railway crossing, taken on the line 2—2 of Fig. 1.

The numeral 1 designates the ordinary rails of the railway, 2 the outside boards or planks of the crossing located as at present 50 close to the head of the rail and flush with the top of said head, 3 the boards or planks of the crossing inside of the said rails, 4 the supports for said boards or planks, and 5 the usual cross-ties of the railway track, 55 arranged to support said rails, parts 4, and planks 2 and 3.

Said planks 3 do not extend to said rails 1, and in the space between said rails and the edge of the nearest plank 3 I locate any suitable metallic chamber for receiving and 60 protecting one edge of a spring-held guard bar or plate 6, 7.

The said chamber is designated by the numeral 8, and in the present form of my invention it is made L-shaped in cross-section, and is fitted with a thin metallic cover 9, between which and the underlying base of said chamber 8 the said guard-bar 6 moves toward and from the adjacent rail as it is actuated by the passing car-wheels 70 and locomotive-wheels.

Suitable springs 11 are located in, and protected by, the walls and cover of the said chamber 8, so, as to bear at all times against the inner edge of the said guard-bar 6, and 75 yieldingly hold the latter close to the adjacent head of the rail 1, and thereby prevent the entrance of a person's shoe-heel or other object into the space between the rail and the said guard-bar.

The edge of said guard-bar that is next to the said rails 1 is provided with a slightly-raised flange 7, and this flange, as well as the ends of said guard-bar, are curved from the rails, in order that the flanges of the 85 car and locomotive wheels will strike said curved portions and force the guard-bars inwardly against the power of said springs, and thereby permit the cars and locomotives to pass without running upon the said 90 guard-bar.

After the car-wheels have passed said guard-bars the said springs will act to return said bars to their normal and usual position, which is as shown, close to the 95 heads of the rails 1.

Suitable screws or other fastenings 10 are used to fasten the said chamber 8 to the said supports 4.

There being nothing to limit the movement of the said guard-bars 6, 7 toward said rails 1 it is evident that the normal position of said bars is in contact with the heads of said rails, so that dust, dirt, rain and snow will be excluded by such contact from the space beneath the overhanging outer edges of the bars and the adjacent parts of the rails; thereby conducting to certainty of operation at all times, there being no opening through which snow and dirt can enter 110 said space, except during the passage of the locomotive or car wheels.

I claim:

In combination with a railway-crossing, and the rails and planks thereof, a metallic chamber that is L-shaped in cross-section, a thin metallic cover for said chamber, a series of coiled springs mounted in said chamber beneath said cover, and a guard-bar mounted with one of its edges in said chamber and its opposite edge normally held yieldingly

in contact with one of the said rails by the 10
said springs.

In testimony whereof I have signed my
name to this specification in presence of
two subscribing witnesses.

JULIUS MALLETT.

Witnesses:

PHILIP A. BADE,
JOHN C. HIGDON.
